UNITED STATES PATENT OFFICE.

JOHN S. ARMOUR AND GIUSEPPE MORETTI, OF PITTSBURGH, PENNSYLVANIA.

DESIGN FOR A MEMORIAL TABLET.

51,850.

Specification for Design.

Patented Mar. 12, 1918.

Application filed December 26, 1917. Serial No. 208,999. Term of patent 7 years.

To all whom it may concern:

Be it known that we, JOHN S. ARMOUR and GIUSEPPE MORETTI, both citizens of the United States, residing at Pittsburgh, Allegheny county, Pennsylvania, have invented a new, original, and ornamental Design for a Memorial Tablet, of which the following is a specification, reference being had to the accompanying drawing, forming a part thereof.

The figure is a face view of a memorial tablet illustrating our new design.

We claim:

The ornamental design for a memorial tablet as shown.

JOHN S. ARMOUR.
GIUSEPPE MORETTI.

Witnesses:

VIOLET M. SCHMID,
JAN CHAPIN.
